CLAIM

The ornamental design for a chair, as shown and described.

DESCRIPTION

FIG. 1 is a front perspective view of a chair showing my new design;

FIG. 2 is a side view, the opposite side view being a mirror image thereof;

FIG. 3 is a front elevational view thereof;

FIG. 4 is a rear elevational view thereof;

FIG. 5 is a right rear perspective view thereof;
FIG. 6 is a left front perspective view of a second embodiment; and,

FIG. 7 is a side view of the second embodiment, the opposite side view being a mirror image.

The rear view of the second embodiment has not been shown and forms no part of the claimed design.
